SOFA

John J. Lubberts and Lambert J. Mulder, Grand Rapids, Mich., assignors to Tomlinson of High Point, High Point, N. C., a corporation of North Carolina

Application April 9, 1957, Serial No. 45,646

Term of patent 14 years

(Cl. D15—11)

The dominant feature of the design resides in the rear panel sections as best shown in Fig. 2 of the drawing.

We claim:

The ornamental design for a sofa, substantially as shown and described.
